United States Patent [19]

Maladra et al.

[11] Des. 263,722

[45]  Apr. 6, 1982

[54] CASH REGISTER HOUSING

[75] Inventors: Anthony Maladra, Moorestown; Adolf Frohlking, Willingboro; George Horton, Englewood, all of N.J.

[73] Assignee: Comtrex Systems Corporation, Mt. Laurel, N.J.

[] Term: 14 Years

[21] Appl. No.: 169,891

[22] Filed: Jul. 17, 1980

[51] Int. Cl. .... D18—99

[52] U.S. Cl. D18/4

[58] Field of Search .... D18/3, 4, 7, 11; D14/42, 43, 45; 235/1 D

[56]

References Cited

U.S. PATENT DOCUMENTS

D. 227,928 7/1973 Forsythe D18/4
D. 231,122 4/1974 Kaufman et al. D18/4

Primary Examiner—Lester L. Lee

Attorney, Agent, or Firm—Duffield & Lehrer

[57]

CLAIM

The ornamental design for a cash register housing, substantially as shown and described.

DESCRIPTION

FIG. 1 is a perspective view of the cash register housing showing our new design;

FIG. 2 is a right side elevational view thereof;

FIG. 3 is a rear elevational view thereof, and

FIG. 4 is a bottom plan view thereof.

Fig. 1Fig. 2Fig. 3Fig. 4